ARCHER LE ROY BOLTON, OF NORTH ANDOVER, MASSACHUSETTS, ASSIGNOR TO JOHN W. BOLTON AND SONS, INC., OF LAWRENCE, MASSACHUSETTS, A CORPORATION OF MASSACHUSETTS.

REMOVABLE LINING SHELL FOR JORDAN ENGINES.

Application filed June 29, 1922. Serial No. 571,720.

This invention relates to what are known as Jordan engines used in the art of refining stock in the manufacture of paper. The purpose of a Jordan engine is to reduce or 5 grind the pulp into small broken fragments.

Such engines include a shell in the form of a truncated cone from which inwardly project knives which cooperate with bars fastened to a truncated conical plug revolvable 10 on a shaft inside the shell.

This invention has to do with the shell and the manner of originally producing the cutting surfaces or knives and the manner of replacing them.

15 The usual method at present is to alternately locate knives and woods with occasional wedges all around the inner surface of the permanent shell, and then drive the wedges into position. The elasticity and 20 swelling of the wood is depended on to hold them in place. I am aware that shells have been made with no woods and with knives integral with the shell, and that various expedients have been used to avoid the long 25 process of accurately setting the knives and woods in the shell at the paper mill, either originally or for replacement.

The purpose of my invention is to provide 30 a lining for Jordan engines which can be completely built up in the machine shop where such shells, their knives or woods, are made and shipped to the paper mill where it is to be used, so that it can be put in place 35 with great rapidity either originally, to replace a similar shell the knives of which are worn down or to take the place of worn out knives and separators.

I accomplish this purpose generally by 40 using an auxiliary filling shell preferably 45 consisting of thin sheet metal made either in one section to fill the entire shell of the engine or in a plurality of sections according to conditions. Inside this shell at the machine shop I build up the knives and woods, holding all in position until complete after 50 which, as the resulting shell is relatively very light, it can be easily shipped to the factory and substituted for the woods and knives in a working shell or replace another similar lining in a permanent shell.

I prefer to use for my removable shell, a case of thin rolled steel of high tensile

strength but may use any thin metal of high tensile strength, together with knives spot-welded thereto and wood separators between 55 the knives, but I may omit the spot-welding or use screws or rivets and I may use separators of other material than wood.

I may use one complete removable shell or several each of truncated cone shape, or several of segmental form.

In the drawings, Figure 1 is a perspective view showing the permanent shell of a Jordan engine, with the plug and plug shaft removed and with one type of my removable lining shells inserted partway into the large end of the permanent shell.

Fig. 2 is a diagrammatic view of the end of a form in which the thin metal case of my lining shell, preferably, is placed while the 70 knives and separators are being fitted and fixed in position at the machine shop.

Fig. 3 is a detail end section showing part of such a lining shell with its thin metal case, knives, separators, and a wedge.

Fig. 4 is an outside view of part of a lining shell in which the knives are spot-welded to the case.

Fig. 5 is a diagrammatic vertical section showing the inside of a shell in which there 80 is more than one set of knives and separators together with the platen of a press showing how knives and separators of each section can be forced or wedged into position all together.

Fig. 6 is a sectional detail showing part of the permanent shell and part of my lining shell, with one method of fastening them together.

Fig. 7 is a section through a permanent 90 shell in the plane where the end of one of my sectional lining shells terminates, such lining shell being of the split type.

Fig. 8 is a plan view and Fig. 9 an end view of a separator of a well known type.

Fig. 10 is a perspective view showing one 95 segmental lining shell and part of adjoining lining shell of one type, with one type of device for holding such segmental section while shipping.

In the drawings, A represents the base or frame of a Jordan engine as used in a paper mill, with the bearing C for the plug shaft and the permanent shell B supported by

brackets 9 and 10 all in a well known manner.

F represents the preferred type of my lining shell and includes a case 19 of truncated conical form which may be made of steel or other suitable metal as thin as one-sixteenth of an inch.

Into this case are forced the knives 30 and woods 31 as by means of wedges 32 in a well-known manner, preferably, while the case 19 itself is held rigidly in a suitable form such as indicated at L in Fig. 2.

After the lining shell F is completely built up in this manner, I prefer to spot-weld at 33 from the outside the knives 30 to the case 19 whereby they are not only firmly held in position but make more rigid the entire construction.

Instead of using such wedges as 32 I may, 20 as shown in Fig. 5, fix each of the several sets of knives and wedges, such as 40 and 41 or 30 and 31, in the following manner. Below the line Y—Y is a section set in position and fixed in the same manner as that above the line X—X now to be described.

The knives 30 and woods 31 are placed accurately but lightly in position, reaching down to the line X—X which is a short distance from the line Y—Y. After all are in place, the platen or plunger G of an hydraulic press is brought down upon the top ends of the knives and woods, and they are gradually forced down and into position so that eventually they reach the line Y—Y.

35 This might be done by an hydraulic press or by applying pressure in any other way as by hammering.

Fig. 6 shows one method of fastening the lining shell F to the permanent shell B by 40 a screw 35.

As shown in Fig. 7, instead of using a continuous lining such as F I may use several shells one for each set of knives and woods, each of such sections as H being split and 45 having its ends turned up at 60 and 61 to hold the knives and woods in position. After putting this in position in the permanent shell B, a fastening wedge such as 45 is driven in to firmly hold the parts H and B 50 together.

Fig. 8 shows a plan view of a common form of separator which may be of wood or other suitable material, and Fig. 9 is an end view of the same. It will be observed that 55 both views show a wedge-shaped and keystone construction well known in the trade.

In such permanent shells there are often several sets of knives and separators arranged in truncated cones end to end, as indicated in Fig. 7 which shows one of such sections.

Instead of building up each annular or substantially annular section complete in the machine shop in a continuous case, such as 60 shown in Figs. 1 and 2, or a split case such

as H shown in Fig. 7, I may use a segmental construction such as shown in Fig. 10.

In Fig. 10, L represents a metal case of a shape to fit part of the inside of a permanent shell, such case having the large curved end 73, the small curved end 72 and the straight edges 70 and 71. With this construction I may use retaining bars of metal such as 74 and 75, which extend along each straight edge 70 and 71 and project inwardly 75 therefrom, and I may attach them to case L by welding, riveting or by bolting, so as to make them firm.

Between these bars, the knives 79 and separators 78 are fitted by wedging or in other 80 suitable manner. Bars 74 and 75 will hold them in position even when the lining segment is removed from the form in which it is built up, but to avoid possible displacement I prefer to use at each end connecting 85 bars such as M which may have nail points 80, 80 which are driven into the separators 78, 78 which are proximate the bars 74, and 75 if such separators are of wood.

I show also passing through each bar such 90 as 74 and 75 as well as through the edges 70 and 71 of case L, half-holes 76 and 77 which register, whereby bolts can be passed through into the permanent shell to hold the parts together if it is found necessary 95 so to do.

Instead of spot-welding or otherwise welding all of the knives, such as 79, to the case such as L, I may fasten some of the knives by means of screws such as 82 which pass 100 through the case L into the back of each knife and I may leave others unfastened.

The fastening of the knives to the case by welding or otherwise, stiffens and strengthens the whole construction, but in many cases 105 is not essential.

I claim:

1. In a Jordan engine having a permanent shell, the combination of a bodily removable lining shell, comprising a case of thin rolled steel of high tensile strength of a shape to fit inside said permanent shell, knives and wooden separators fitted to the inside thereof, said knives being spot welded to the case, and means to fasten the lining shell and permanent shell 110 detachably together.

2. A bodily removable lining shell for the permanent shell of a Jordan engine, comprising a case of thin rolled steel of high 120 tensile strength of a shape to fit inside said permanent shell, knives and wooden separators fitted to the inside thereof, said knives being fastened to the case, and means to fasten the lining shell and permanent shell 125 detachably together.

3. A bodily removable lining shell for the permanent shell of a Jordan engine, comprising a case of thin rolled steel of high tensile strength of a shape to fit inside said 130

permanent shell, knives and wooden separators fitted to the inside thereof, said knives being fastened to the case.

4. In a Jordan engine having a permanent shell, the combination of a bodily removable lining shell, comprising a case of thin metal of high tensile strength of a shape to fit inside said permanent shell, knives and separators fitted to the inside thereof, said knives being spot welded to the case, and means to fasten the lining shell and permanent shell detachably together.

5. A bodily removable lining shell for the permanent shell of a Jordan engine, comprising a case of thin metal of high tensile strength of a shape to fit inside said permanent shell, knives and separators fitted to the inside thereof, said knives being fastened to the case, and means to fasten the lining shell and permanent shell detachably together.

6. A bodily removable lining shell for the permanent shell of a Jordan engine, comprising a case of thin metal of high tensile strength of a shape to fit inside said permanent shell, knives and separators fitted to the inside thereof, said knives being fastened to the case.

7. A bodily removable lining shell for the permanent shell of a Jordan engine, comprising a case of thin metal of high tensile strength of a shape to fit inside said permanent shell, knives and separators fitted to the inside thereof, some of said knives being fastened to the case.

8. A bodily removable section of lining shell for Jordan engines comprising a thin metal case of a shape to fit part of the inside of the permanent shell having oppositely disposed curved edges and oppositely disposed straight edges, with retaining means for knives and wooden separators along its straight edges, combined with a plurality of said knives and wooden separators which are fitted to the inside thereof some of said knives being spot welded to said case, and means to fasten said section of lining shell and the permanent shell together.

9. A bodily removable section of lining shell for Jordan engines comprising a thin metal case of a shape to fit part of the inside of the permanent shell having oppositely disposed curved edges and oppositely disposed straight edges, with retaining means for knives and separators along its straight edges, combined with a plurality of said knives and separators which are fitted to the inside thereof, some of said knives being fastened to said case, and means to fasten said section of lining shell and the permanent shell together.

10. A bodily removable section of lining shell for Jordan engines comprising a thin metal case of a shape to fit part of the inside of the permanent shell having oppositely disposed curved edges and oppositely dis-

posed straight edges, combined with a plurality of knives and wooden separators which are fitted to the inside thereof some of said knives being spot welded to said case.

11. A bodily removable section of lining shell for Jordan engines comprising a thin metal case of a shape to fit part of the inside of the permanent shell, combined with a plurality of knives and separators which are fitted to the inside thereof, some of said knives being fastened to said case.

12. A bodily removable lining shell for the permanent shell of a Jordan engine, comprising a case of thin metal of high tensile strength of a shape to fit inside said permanent shell, and knives and separators fitted to the inside thereof.

13. A bodily removable section of lining shell for Jordan engines comprising an elastic thin metal case of a shape to fit part of the inside of the permanent shell having oppositely disposed curved edges and oppositely disposed straight edges, with retaining means for knives and separators along its straight edges, combined with a plurality of said knives and separators which are fitted to the inside thereof, some of said knives being fastened to said case, and means to fasten said section of lining shell and the permanent shell together.

14. A bodily removable section of lining shell for Jordan engines comprising an elastic thin metal case of a shape to fit part of the inside of the permanent shell, combined with a plurality of knives and separators which are fitted to the inside thereof, some of said knives being fastened to said case.

15. The combination with the permanent shell of a Jordan engine: of a bodily removable preconstructed filler lining therefor adapted to be inserted, expanded and maintained within said permanent shell, including a series of knives and separators arranged in alternating relation, and held together peripherally but split longitudinally; a wedge adapted to be inserted between the adjacent edges of said split and operable to expand said filler or lining when placed in operative position within said permanent shell.

16. A shell lining for a Jordan engine including in combination, a jacket conforming approximately in size and shape to the inner conformation of a section of the shell, a plurality of blades and blade spacing elements adapted to be assembled in said jacket to effect a shell lining unit, means to effect fixed relation between said assembled parts and said jacket, and means to expand the lining unit to effect fixed relation thereof with said shell.

17. A shell lining for a Jordan engine including in combination, an expandable jacket shaped to conform to an inner section of the shell, a plurality of blades and blade spac-

ing elements adapted to be assembled in said jacket to effect a shell lining unit, and means, as a wedging element adapted to be forced between adjacent lining parts to expand the unit and effect fixed relation thereof with said shell.

18. The herein described method of lining Jordan engine shells consisting in provid-

ing an expandable jacket conforming in size and shape as expanded to an inner section 10 of the shell, in assembling the lining elements in said jacket and in effecting fixed frictional relation between the assembled elements and said jackets without expanding the jacket to form a lining unit.

ARCHER LE ROY BOLTON.
